SEWED END VALVE BAG

Harry Stanley Hangen, North Tarrytown, N. Y.,
assignor to St. Regis Paper Company, New
York, N. Y., a corporation of New York

Application March 4, 1938, Serial No. 193,969

2 Claims. (CL 229—62.5)

This invention relates to a valve bag, and more particularly to an improvement whereby the closing of the valve is facilitated.

Details of the invention will appear as the description proceeds.

In the accompanying drawing forming a part of this specification,

Fig. 1 is an elevation of an empty bag with parts broken away for purposes of illustration;

Fig. 2 is an enlarged section on the line 2—2 of Fig. 1;

Fig. 3 is a section upon substantially the same line as Fig. 2, but showing only a two-ply bag in the position which it occupies after being filled.

For convenience, this invention has been shown 15 in connection with a bag of the type described and patented in the patent to Bates and Cornell, No. 1,752,292, issued April 1, 1930, but it will be readily understood that the improvements which constitute this invention may be applied to any 20 valve in the corner of a bag where the valve is collapsed laterally and expanded longitudinally of the bag when the bag is empty and is spread laterally and collapsed longitudinally of the bag when the bag is filled. The invention relates to 25 an improvement which facilitates the change in the shape of the valve when the bag is filled.

In the drawing referred to there is shown a bag 18 closed at the upper end by a reinforced seam 11; the side of the bag is provided with a gusset 12, and at the upper end of the gusset the corner of the bag is folded in to form a valve 13. The construction so far described is in accordance with the bag disclosed in the aforesaid patent.

In the improved construction shown, the sides 35 of the valve are adhered to the inner surfaces of the bag walls at 14. When the bag is filled and expanded the side walls are spread apart and bent along the lines 15, which may be referred to for convenience as "shoulders." For best results 40 the adhesive between the valve and the bag walls should extend at least close to the shoulder line. In the construction shown in Figs. 1 and 2, the adhesive is extended at 16 somewhat below the shoulder line. When the bag is filled and the bag walls are separated and bent outward to the position in which they are shown in Fig. 3, the walls 45 of the valve are likewise spread laterally. The adhesive at 16 is torn away to the shoulder line. The strain of this tearing-away insures the 50 spreading of the valve.

In the form shown, the edges of the valve are shown slit at 17 at the ends of where folds 15 will occur. Likewise, the edge of the valve is shown slit at 18 where the fold occurs when the bag is 55

empty, and at the point where the wall of the valve must be straightened when the valve is spread to the position in which it is shown in Fig. 3. These slits at the ends of the fold lines lessen the 5 resistance of the paper or like material to bending along these lines, and therefore reduce the resistance to a spreading of the valve to the form in which it is shown in Fig. 3, and this assists the action of the adhesive in securing a proper closing of the valve.

In the absence of adhesive 14 or its equivalent, the material of the valve may fold along irregular lines or at improper places, so that sometimes openings are left through the valve where material may escape. It will be readily seen that when the valve is properly spread as indicated in Fig. 3 the lower layer of the valve lies flat against the upper layer of the valve and securely closes the outlet.

Bags of this type are customarily made of a plurality of layers of paper. Where adhesive is employed as shown in Figs. 1, 2 and 3 between the inner layer of the wall and the adjacent layer of the valve, the spreading of the exterior layer of the valve is insured. Usually the inner layers of the valve follow the movement which the outer layer is thus compelled to take, so that the valve is properly closed. However, it sometimes happens that the inner layers of the valve, if left unattached to the outer layers, may fail to follow the movement of the outer layers, and this may result in imperfect closing of the valve. Where particularly perfect closing is necessary, and especially where there are a good many layers of paper so that the inner layer of the bag wall is relatively thin compared to the total thickness of the bag wall, it may be worth while to secure the several layers together in the valve wall, or the bag wall, or both. This may be done by adhesive between the plies.

Spots of adhesive may be used instead of the relatively extended complete layer indicated in the drawing, and other obvious changes may be made within the scope of the appended claims.

What I claim is:

1. A bag having its end closed by a straight-line seam and the corner of the bag at one end of the seam folded in to form an inwardly extending valve sleeve substantially parallel with said seam, the valve being spread longitudinally of the bag when the bag is empty and collapsed and being arranged and proportioned to normally collapse laterally of the bag when the bag is filled with the folded edges of the valve substantially at the shoulders of the filled bag, and the

sides of the bag being adhered to the walls of the bag along the lines that form the shoulders of the filled bag and for a short distance on the side of said line away from said seam, the adhesive being of a character that tears away to said lines when the filled bag walls are spread apart to form shoulders, thereby allowing the bag walls to spread without injury to the walls and bag

and insuring the flattening of the wall between the shoulders when the bag walls are spread.

2. A bag in accordance with claim 1, and having slits at the end of the valve along the shoulder lines and the line where the sleeve is folded parallel to the seam in the collapsed, empty bag, the sleeve being relatively stiff where not slit.

HARRY STANLEY HANGEN.
